GRATE CLEANING MECHANISM FOR LOOMS

Frank D. Herring, Talladega, Ala., assignor to
Draper Corporation, Hopedale, Mass., a corporation of Maine

Application July 20, 1932. Serial No. 623,640

4 Claims. (Cl. 139—377)

The present invention relates to looms and more especially to improved means for preventing certain imperfections in cloth, known as thin places, during the process of weaving.

5 A primary object of the present invention is to provide a new and improved filling motion hook which has associated with it means that co-act with the loop detector for maintaining the filling grate clean of lint, waste, strings or other 10 foreign matter, thus insuring an efficient operation of the loom and preventing thin places being formed in the cloth during the process of weaving.

A further object comprehends the provision 15 of simple, efficient and economical means for preventing the accumulation of foreign matter in the filling grate, thereby eliminating the necessity of requiring the grate being periodically cleaned or brushed.

20 Other objects and advantages of the invention will become apparent from the following description, taken in conjunction with the accompanying claims and drawing.

Referring to the drawing, in which is shown a 25 preferred embodiment of the invention,

Figure 1 is a side elevation partly in section of a filling fork-slide and its associated parts with my invention applied thereto and with the slide in its detecting position.

30 Figure 2 is a view similar to Figure 1, with the parts moved to their non-detecting position.

Figure 3 is an enlarged perspective view of my improved filling motion hook and its connection with the detector loop.

35 Referring to the drawing in which like numerals indicate like parts in the several views, 10 designates a stand or support which is fixedly connected to a portion of the loom such as the breast-beam (not shown). Slidably mounted on 40 the stand 10 is the filling fork-slide 11 that has a forked extension 12 between the arms of which is connected the filling fork loop detector 13 by the pin 14.

A vibrating actuator 15 in the form of a weft 45 hammer or cam follower dog is preferably pivotally connected to the loom in the usual manner (not shown) so as to be moved towards and from the front of the loom. The upper end portion of the actuator 15 extends between the forked arms 50 of the extension 12 and has pivotally connected thereto by the pin 16, the filling motion hook 17, which preferably is provided with an elongated slot 18 having an entrance opening 19, so as movably to receive the cross-bar 20 connected to the 55 forked arms of the extension 12. It will be seen

that the bar 20 acts as a support or rest piece for the hook 17 during the movement of the parts when the loom is in operation.

The upper surface of the hook 17 is preferably formed with a substantially straight longitudinal portion 21, which terminates in an upwardly projecting shoulder or hook 22 that in turn extends downwardly as at 23. The inclined portion 23 terminates at the free or outer end of the hook at a point below the longitudinal portion 21. A 60 yieldable member in the form of a spring 24 is preferably connected to the upper surface of the hook 17 by the screw 25 (Fig. 3) and may be formed with a loop or curved portion 26, which has an outwardly inclined arm 27, bent as at 28, 65 to engage yieldably the adjacent end or corner 29 of the upper surface of the hook. The free end 30 of the spring may extend below the hook 17 so as to terminate in a flange 31.

A filling fork grate 32 provided with the spaced 75 openings 33 may be connected to the bracket 34 carried by the lay beam 35, in any suitable manner such as by the screw 34' (Fig. 2), so as to be movable with the beam 35 when the lay beats up. The detector 13 has its depending prongs or tines 80 36 arranged to move within the openings 33 of the grate 32 when the weft thread 37 (Fig. 1) is not present. The loop 38 of the detector rides upon the upper surface of the hook 17, so as to assume the position as shown in full lines in Figure 1, when the parts are in their detecting position and be moved to the position as shown in Figure 2, when the parts are moved to their non-detecting position.

85 As is customary in the operation of devices of this character, when the prongs 36 detect by the weft thread 37, the detector 13 is tilted due to the fact that the prongs cannot enter into the openings 33 of the grate 32, since the thread is drawn across the grate between the grate and 90 the prongs. This tilting of the detector moves the loop 38 upwardly out of engagement with the shoulder 22, so as to cause it to assume the dotted line position, as shown in Figure 1, thereby allowing the actuator or weft hammer 15 to move on 95 its forward or detecting stroke without causing replenishing of weft thread into the shuttle or cutting the loom off, in a manner well known to those skilled in the art.

100 When the loop 38 is in detecting position, as shown in full lines in Figure 1, it is in the path of the shoulder 22 and the spring 24 yieldably engages the outer end of the hook as at 29. If the weft thread 37 is present, that is to say is not broken or run out, the movement of the grate 105 32 110

5 towards the filling fork prongs 36 moves the weft thread 37 against the prongs, thus preventing the latter from entering into the openings 33, thereby by moving the detector 13 to its dotted line position, as shown in Figure 1, which allows the continued operation of the loom without replenishing of the weft thread in the shuttle. On the other hand, if the weft thread is not present adjacent the grate 32, the fork prongs 36 pass into the openings 33, thus allowing the loop 38 to remain in engagement with the shoulder 22 of the hook 17, so as to put into operation the mechanism to either replenish the weft thread or stop the loom. Devices of this character as heretofore 10 made, have been open to the objection that, while the weft thread may be absent when the parts are in the position such as shown in Figure 1, not infrequently some other obstruction such as lint, waste, or strings accumulate in the 15 openings 33 of the grate, which foreign matter pushes the fork prongs 36 forwardly in the same manner as if the weft thread 37 were present, thus allowing the loom to continue operation and not stop or be replenished with a weft thread. Such 20 operation draws through the warp thread without the weft thread, causing imperfections known as thin places in the cloth during the weaving process which materially lower the quality and value of the woven fabric.

30 In order to overcome the deficiencies of devices of this character as heretofore made and to insure the fabric or cloth being formed free from thin places, I have provided a novel filling motion hook 17 and have associated with the hook a yieldable member 24 which co-acts with the loop 38 of the detector 13, to force the prongs 36 an appreciable distance within the openings 33 of the grate 32 on the non-detecting or backward stroke of the weft hammer 15, as shown in Figure 2, in order to maintain the grate openings 40 32 clean and free from obstructions such as lint, waste, string and the like.

45 It will be noted that the formation or design of the hook 17 is substantially different from similar types as heretofore made, in that it is thicker or wider at the point where the loop 38 rests against the shoulder 22 when in detecting position (Fig. 1), thereby holding or supporting the loop 38 on a higher level in its detecting 50 position than the hooks heretofore employed. By reason of the raising or elevating of the supporting plane for the loop 38 when the parts are in their detecting position as shown in full lines in Figure 1, the prongs 36 will not project as far into the grate 32 as they would if the loop 38 were supported at a lower level. Additionally, the inclined upper surface 23 on which the loop 38 rests at the end of the non-detecting stroke (Fig. 2) is shaped to allow the loop 38 to drop to a lower level at this point than that which it 55 assumes on the detecting stroke (Fig. 1). In other words, the portion 29 of the hook is below the level or plane of the straight portion 21, thereby allowing the prongs 36 normally to project farther into the openings 33 of the grate than has heretofore been possible. It will be seen that due to the farther advancement of the prongs 36 into the openings 33 that means are provided for moving or knocking clear any obstructions that might collect therein and would 60 tend, if not removed, to interfere with the efficient operation of the loom on the next or detecting stroke.

65 When the parts are in the position as shown in Figure 2, the portion 28 of the spring 24 presses

80 downwardly against the adjacent end of the loop or tail 38, which, in turn, tends to move or force the prongs 36 farther into the openings 33, so as to force out or remove any obstruction which may be collected therein.

85 Should the shuttle come in contact with the prongs 36 the spring 24 is sufficiently flexible or yieldable to allow the loop 38 to raise to a height sufficient to prevent bending of the prongs 36 or the loop 38. The flange 31 on the free end of the spring 24 acts as a catch to prevent the loop 38 from moving under and riding on the upper surface of the spring 24 when the shuttle contacts with the prongs 36.

90 It will, therefore, be seen that by reason of the present invention the filling motion hook 17 and the detector 13 have associated therewith means operating on each alternate, non-detecting pick for forcing the prongs an appreciable distance within the openings 33 of the grate 32, thus preventing the collection of lint, waste, strings or other foreign matter on the grate and eliminating the necessity of periodically cleaning or brushing the grate as has heretofore been necessary. Additionally, by providing means for preventing 100 thin places being formed in the cloth during the weaving process the woven fabric will be of more uniform and better quality.

105 It is to be understood that the form of the invention shown and described is merely illustrative of a preferred embodiment and that such changes may be made as fall within the purview of one skilled in the art without departing from the spirit of the invention and the scope of the 110 appended claims.

110 I claim:

115 1. A thin place preventing mechanism for looms having in combination a stand connected to the loom, a filling fork-slide mounted on the stand and having a forked extension connected by a cross-bar, a detector pivotally connected to the end of the extension, said detector having depending prongs and a laterally extending loop, a movable filling grate associated with the detector and arranged to receive said prongs, a weft 120 hammer projecting through the fork-slide extension and having a filling motion hook pivotally connected thereto, said hook having an elongated opening for receiving said cross-bar to movably support the hook within the fork-slide, said hook 125 having its upper surface formed with a shoulder portion and a rearwardly inclined portion, the loop of said detector arranged to engage the upper surface of said hook, and yieldable means connected to said hook and arranged to engage said loop during each alternate, non-detecting pick whereby the loop is yieldably moved to a lower level during each of said non-detecting picks than it occupies during the detecting picks.

130 2. A thin place preventing mechanism for 135 looms having in combination a stand connected to the loom, a filling fork-slide mounted on the stand and having a forked extension connected by a cross-bar, a detector pivotally connected to the end of the extension, said detector having depending prongs and a laterally extending loop, a movable filling grate associated with the detector and arranged to receive said prongs, a weft hammer projecting through the fork-slide extension and having a filling motion hook pivotally connected thereto, said hook having an elongated opening for receiving said cross-bar to movably support the hook within the fork-slide, said hook 145 having its upper surface formed with a shoulder portion and a rearwardly inclined portion, the 150

loop of said detector arranged to engage the upper surface of said hook, and spring means connected to said hook and arranged to engage said loop when said hook is in its non-detecting position whereby to move the fork prongs an appreciable distance within the grate to keep the grate openings free from obstructions. 5

3. A thin place preventing mechanism for looms having in combination a stand connected to the loom, a filling fork-slide mounted on the stand and having a forked extension connected by a cross-bar, a detector pivotally connected to the end of the extension, said detector having depending prongs and an outwardly extending loop, a movable filling grate associated with the detector and arranged to receive said prongs, a weft hammer projecting through the fork-slide extension and having a filling motion hook pivotally connected thereto, said hook having an elongated opening for receiving said cross-bar to movably support the hook within the fork-slide, said hook having its upper surface formed with a shoulder portion and a rearwardly inclined portion, the loop of said detector arranged to engage the upper surface of said hook, a spring connected to the upper surface of said hook at the forward end thereof and extending upwardly and downwardly over the opposite end, said spring arranged to engage said loop when the said hook is in its non-detecting position for moving the filling fork prongs into the grate openings to prevent foreign matter from collecting thereon. 80

4. A filling motion hook for looms arranged to be operatively associated with a filling fork loop detector, said hook having its upper surface provided with a substantially straight longitudinal portion and a downwardly inclined portion, said portions being connected by an upwardly projecting shoulder, the loop of the detector arranged to engage said upper surface, and yieldable means connected to said hook and engaging one end thereof to move said loop during each alternate, non-detecting pick to a lower level than the loop occupies during the detecting picks. 85
